Inventor:

Edward J. Colby
By James W. Park,
Attorney

UNITED STATES PATENT OFFICE.

EDWARD J. COLBY, OF CHICAGO, ILLINOIS.

COIN-RELEASED SPIROMETER.

SPECIFICATION forming part of Letters Patent No. 406,089, dated July 2, 1889.

Application filed July 30, 1888. Serial No. 281,459. (No model.)

To all whom it may concern:

Be it known that I, EDWARD J. COLBY, a citizen of the United States, residing at Chicago, in the county of Cook and State of Illinois, have invented a certain new and useful 5 Coin - Controlled Lung - Testing Device, of which the following is a specification.

My invention relates to devices for testing the lungs, and has for its object to provide a simple, cheap, and convenient device for this purpose, so that the same cannot be operated except upon insertion of a coin.

My invention is illustrated in the accompanying drawings, wherein I have shown the same with certain modifications.

Figure 1 is a front view of the machine. Fig. 2 is an interior view of the machine when at rest. Fig. 3 is an interior view of the machine when in operation. Fig. 4 is a diagrammatic view of the machine at the moment when it is put in operation. Fig. 5 is a cross-section detail of the coin-receiving slot. Fig. 6 is an interior view of a modification, showing a bellows instead of a cylinder. Fig. 7 is 25 a similar view with the parts in operation. Fig. 8 is a cross-section of a modification. Fig. 9 is a side view of the same.

Like parts are indicated by the same letter in all the drawings.

30 A is a dial, upon which is the pointer-index A' and the slot A², of the proper size and shape to receive the coin.

A³ is the base, and A⁴ the case.

A⁵ is an air-tube, A⁶ the mouth-piece, and 35 A⁷ a bracket for supporting the mouth-piece.

A⁸ are scale or index marks on the dial.

Connected with the slot A² is the way B, beneath which is the receptacle B', pivoted at B² and provided with a hook B³ at its other 40 extremity.

Connected with the tube A⁵ is the tube C, which terminates in the cylinder C'. Within this cylinder and projecting therefrom is the rod C², having the rack C³ thereon and passing through the guide C⁴.

The pointer A' is secured on the shaft D, at the inner extremity of which is fixed the pinion D' and the cam-wheel D², having the notch D³ in its periphery. The pinion D' engages 45 the rack C³.

Beneath the receptacle B' is the guide E,

which conducts the coin to the lower part of the case.

F is a coin.

On the rod C² and within the cylinder C' is 55 the spiral spring G, fixed between the bottom of the cylinder C' and the cap G' on the top of the rod C², so as to hold the rod C² normally in its elevated position. The cap G' operates as the piston moves in the cylinder C' under 60 the pressure of the air forced in through the pipe A⁵ and pipe C.

In the modification shown in Figs. 6 and 7 the tube A⁵ terminates within the tube H, which opens into the lower portion of the bellows H'.

To the upper end of the bellows H' is secured the cord H², which passes about the pulley H³ and thence to the rack-rod H⁴. This latter engages the pinion D'. The rack-rod 70 H⁴ is smooth at its upper end, is encompassed by the spiral spring H⁶, and terminates above in the cap H⁷ and passes through the guide H⁵, so that it is kept normally elevated, as indicated in Fig. 6.

In the modifications shown in Figs. 8 and 9, J is a rock-shaft journaled in the bearings J' J' within the case A⁴. This rock-shaft has one arm K pivoted to the link K', which in turn is pivoted to the push-rod K², which terminates in the button K³. The slot A² in this case terminates in the guide L, through which the coin F passes. This guideway L is provided with a slot L', which receives the link L² from the arm L³ on the rock-shaft J. The 85 guide L is cut away at one side at M to receive the end M' of the elbow-lever M², which is pivoted at M³, and the other end of which M⁴ is provided with the hook M⁵ to receive the notch D³.

90 W is a counter-weight on the edge and near the periphery of the cam D². It is so placed as to be a little off center when the cam D² is locked, and when the cam is released the counter-weight slightly turns the cam, so as to 95 bring the point B³ or M⁵ upon the edge of the cam back of the notch.

The use and operation of my invention are as follows: I will first describe the operation of the device as shown in Figs. 1, 2, 3, 4, and 100 5. The machine as set up is in the condition indicated in Figs. 1 and 2. If, now, a coin be

introduced into the slot A², it will pass into the way B and thence into the receptacle B' and lift the hook B³ from the notch D³, as indicated in Fig. 4. If, now, the person using 5 the same applies the pressure of his lungs through the tube A⁵ and tube C to the cylinder C', that pressure will be applied to the upper part of the cap of piston G', and the same, together with the rod C², will be forced 10 downwardly. The rack C³, by this motion being in engagement with the pinion D', will rotate the same, together with the pointer A', and thus the pressure applied and the strength 15 of the lungs are indicated upon the dial. When the pressure is released, the spring G immediately draws the rod C² up and restores the parts to the position indicated in Fig. 2. The coin in the meantime has passed through the 20 guide E into the base of the case, where it may be removed when desired.

The operation of the parts indicated in Figs. 6 and 7 is substantially the same, with the exception that here the pressure applied from the lungs through the tube A⁵ and tube H to 25 the bellows H' expands the bellows, as shown in Fig. 7, thus drawing the rack-rod H⁴ downwardly, so as to make the pointer indicate the strength of the lungs. When the pressure is released, the spring H⁶ restores the parts to 30 the position shown in Fig. 6.

In Figs. 8 and 9 I have shown a modification whereby not the weight of the coin, but a pressure applied through the coin, is made to release the parts. Thus, by pushing the knob 35 K³ inwardly the rod K⁴ moves, forcing the

link K' inwardly, and thus, by means of the arm K turning the shaft G in its bearings, this same motion forces the arm L³ downward, carrying with it the link L², and this carries the coin which has been introduced 40 into the slot A² into the guide L, resting against the end M' of the elbow-lever M². The pressure applied through the link L² against the coin forces it downwardly through the guide 45 L, turning the rock-shaft M³ on its bearing M⁴ and releasing the hook M⁵ and permitting the parts to operate when the pressure of the lungs is applied. This modification is equally applicable to the form of device shown in Fig. 2 or Fig. 6.

Having thus described my invention, what I claim, and desire to secure by Letters Patent, is as follows:

In a coin-controlled lung-tester, the combination of a dial with indicating-hand thereon and coin-slot therein, with a blowing apparatus, a pinion on the shaft which supports the hand, and a rack connected with such blowing apparatus, a spring to restore such rack to its place after operation, and a pivoted dog and cam which locks such pinion from motion, a coin-slide, an arm from such dog in the path of the coin, and a rock-shaft with arm and push-button, so as to force said coin along its slide, and thus trip the dog and permit the parts to operate.

EDWARD J. COLBY.
